EMBLEM BUMPER CLAMP

Frank M. Marshall, Miami, Fla.

Application November 28, 1955, Serial No. 39,053

Term of patent 14 years

(Cl. D14—6)

Fig. 1.

Fig. 2.

Fig. 3.

The emblem and fragmentary bumper portion shown by means of broken lines are only disclosed for purpose of illustration.

I claim:

The ornamental design for an emblem bumper clamp, as shown and described.
